UNITED STATES PATENT OFFICE.

BENJAMIN WATSON, OF EDEN, NEW YORK.

EXTENSION CAR-STEP.

No. 830,867.

Specification of Letters Patent.

Patented Sept. 11, 1906.

Application filed December 29, 1905. Serial No. 293,747.

To all whom it may concern:

Be it known that I, BENJAMIN WATSON, a citizen of the United States, and a resident of Eden, in the county of Erie and State of New York, have invented a new and Improved Extension Car-Step, of which the following is a full, clear, and exact description.

The purpose of the invention is to provide a very simple, durable, and effective extension attachment for the fixed steps of car-platforms, which attachment is capable of ready and economic application to the fixed steps of any car or like vehicle.

A further purpose of the invention is to so construct the attachment that the extension-step can be quickly brought to its lower position as an extension from the main steps by a single movement of the foot of a trainman on the platform and whereby the extension-step will be automatically carried to its upper or storage position as soon as unlocked from its lower position.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of a portion of a car-platform and its steps, illustrating the application of the extension-step and showing the same in two positions. Fig. 2 is a vertical section taken practically on the line 2 2 of Fig. 3, and Fig. 3 is a vertical section taken at right angles to the sections shown in Fig. 2 and practically on the line 3 3 of Fig. 2.

A represents a portion of the body of a car, B a platform for the same, and C the customary fixed steps carried by the platform. Metal guide devices 10 are secured to the outer faces of the side pieces of the steps C, and the side members 11 of an essentially U-shaped carrier D are held to slide freely in the said guide devices, while the connecting member 12 of the carrier extends beneath the lower fixed step 13. The side members 11 of the carrier are given an inclination corresponding to that of the fixed step C; but the connecting member 12 is flat and is secured in any approved manner longitudinally of 55 and to the under face of an extension-step 14

of the same dimensions as a fixed step 13, and normally the extension-step 14 lies close to the under face of the lower fixed step 13, as is shown by positive lines in the drawings.

The carrier D is limited in its downward movement by forming heads 15 at the upper ends of its side members 11, which when the extension-step is in its position for use bear upon the uppermost guide devices 10. An arm 16, having the same inclination as the fixed step C, is attached to or is integral with the central portion of the connecting member 12 of the carrier, and this arm 16 extends upward at the rear of the fixed steps C, as is best shown in Fig. 2, and may also extend to the forward end of the extension-step 14, as is illustrated at 17 in Figs. 1 and 2, if desired. The arm 16 has upward and downward movement to raise the lower or extension step 14 and in such movement engages with 75 friction-rollers 18, journaled in bearings 19, secured to the back of the fixed steps C, sundry of which rollers engage with the front and others with the rear face of the arm, as is shown in Figs. 2 and 3.

A bracket member is provided for the upper end of the arm 16, extending horizontally outward, as is shown in Fig. 3, and the outer end of the said bracket member is secured to a push-bar 21, which extends up through a suitable guide 22, secured to a sill of the platform and through an elongated slot 23, made in the platform, which slot is preferably provided with a border-plate 24. The push-bar is adapted to be operated by the foot of a trainman and terminates at its upper end in a knob 25, and while the upper end of the push-bar is perpendicular its body portion is given the same inclination or slant as the slant of the fixed steps and of the carrier D. 95 The push-bar is provided with one or more notches 26 in its rear edge, adapted for locking engagement with one edge of the plate 24 or a wall of the slot 23 when the push-bar is forced downward to bring the extension-step 100 to its lower position, from which position the extension-step is returned when the push-bar is released by means of a spring 27, attached to the upper end of the said arm 16 and to the platform, as is shown in Figs. 2 and 3. It will be understood that the guide devices 10 may be provided with friction-rollers to render easy the movements of the carrier D.

Having thus described my invention, I

claim as new and desire to secure by Letters Patent—

1. The combination with a car-platform and the steps fixed thereto, of a carrier mounted to slide at the side portions of the fixed step-support, an extension-step secured to the said carrier at a point below the lowermost fixed step, the extension-step being adapted to drop down and in front of the lowermost fixed step and to be carried up along the said fixed step, a tension device for exerting upward action on the said carrier, an arm connected at the center of the extension-step and having a bracket extending to the side of the fixed steps, and a push-bar connected with the said bracket, said push-bar extending upward through an opening in the platform, and means for locking the push-bar when forced downward.
2. The combination with a platform of a car and the steps fixed thereto, of a substantially U-shaped carrier having its side members mounted for sliding and guided movement on the side supports for the fixed steps, the said side members having heads at their upper ends limiting the downward movement of the carrier, an extension-step secured to the connecting member of the said carrier, the extension-step being located below the lowermost fixed step and adapted for movement to and from the same, an arm extending upward at the rear of the said carrier, a spring connected with the said arm and with the platform, a push-bar connected with the

said arm and extending up through an opening in the platform, and means for locking the push-bar in its lower position.

3. The combination with a car-platform, steps fixed thereto, said platform being provided with an opening therein adjacent to the steps, and guides secured to the outer faces of the side supports of the fixed steps, of a substantially U-shaped carrier, the side members of which are given the same inclination as the fixed steps and are mounted to slide in the guides carried by the said fixed steps, the said side members of the carrier having heads at their upper ends, the connecting member of the said carrier being below the lowermost fixed step, an auxiliary step secured to the connecting member of the carrier, an arm extending up from the rear portion of the carrier and having a side extension, roller-bearings for the said arm, a spring connecting the said arm with the platform, and a push-bar connected with the extension from the said arm, being passed up through an opening in the platform and provided with locking means, the inclination of the push-bar corresponding to the inclination of the fixed steps, as described.

In testimony whereof I have signed my name to this specification in the presence of two subscribing witnesses.

BENJAMIN WATSON.
